(57) **CLAIM**

The ornamental design for a USB drive, as shown and described.

DESCRIPTION

FIG. 1 is a top perspective view of a USB drive of the claimed invention.

FIG. 2 is a bottom perspective view thereof.

FIG. 3 is a front side elevation view thereof.

FIG. 4 is a back side elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dash-dot lines shown in FIG. 3 represent light rays that are emitted from the USB drive of the claimed invention, when activated. In some alternative embodiments, the lighting is not provided. The broken lines are for illustrative purposes only and form no part of the claimed design.
